(57) **ABSTRACT**

A color photographic material having a support and at least one light-sensitive silver halide emulsion layer and at least one color coupler associated with the latter, wherein the silver halide emulsion layer contains at least one compound of formula (I)

wherein

m denotes 0, 1, 2, 3 or 4,

n denotes 2, 3, 4, 5 or 6,

R₁ denotes a di- to hexavalent group,

R₂ denotes alkyl, alkenyl, cycloalkyl, aryl, alkoxy, aryloxy, alkylthio, arylthio, acyl, alkoxy carbonyl, aryloxy carbonyl, hydroxy, halogen, cyano, —SO₂R₅, —SOR₅, —CON(R₅)R₆ or —SO₂N(R₅)R₆,

L₁ denotes alkylene, arylene, aralkylene or alkylidene,

L₂ denotes

L₃, L₄ denote a C₁—C₃ alkylene which is optionally substituted,

R₅ denotes alkyl or aryl, and

R₆ denotes H or R₅, wherein L₂ and X are as defined in the specification, is distinguished by improved stability to light.

14 Claims, No Drawings

COLOR PHOTOGRAPHIC MATERIAL

This invention relates to a colour photographic material having a support and at least one light-sensitive silver halide emulsion layer and at least one colour coupler associated with this layer, which on development with a colour developer forms a dye which is distinguished by improved stability to light due to a new type of dye stabiliser which is added to the layer.

It is known that dyes which are formed on the development of a colour photographic material, particularly magenta dyes, and quite particularly those which are based on pyrazolotriazole magenta couplers, have to be stabilised against their destruction by light. Thus, for example, EP 273 412 and EP 273 712 describe aminophenol ethers with cyclic amine substituents, and EP 457 543 describes the same compounds in combination with bisphenols as stabilisers for an azomethine dye formed from pyrazolotriazole magenta couplers. The effect of these materials, even in combination with other stabilisers, is still not satisfactory.

Compounds have now been found which impart a higher stability to dyes such as these, particularly in relation to light.

The present invention therefore relates to the material cited at the outset, characterised in that in the light-sensitive layers it contains at least one compound of formula (I)

wherein

m denotes 0, 1, 2, 3 or 4,

n denotes 2, 3, 4, 5 or 6,

R₁ denotes a di- to hexavalent group,

R₂ denotes alkyl, alkenyl, cycloalkyl, aryl alkoxy, aryloxy, alkylthio, arylthio, acyl, alkoxy carbonyl, aryloxy carbonyl, hydroxy, halogen, cyano, —SO₂R₅, —SOR₅, —CON(R₅)R₆ or —SO₂N(R₅)R₆,

L₁ denotes alkylene, arylene, aralkylene or alkylidene,

L₂ denotes

L₃, L₄ denote a C₁—C₃ alkylene which is optionally substituted,

X denotes

or

R₃ denotes H, acyl, —SO₂R₅, alkoxy carbonyl aryloxy carbonyl alkyl aryl, alkenyl or the radical of a heterocycle,

R₄ denotes H, alkyl, aryl or the radical of a heterocycle,

R₅ denotes alkyl or aryl, and

R₆ denotes H or R₅, wherein

2 R₃ and R₄ radicals may be the same or different.

Preferably,

R₁ denotes a di- to hexavalent aliphatic or aromatic group,

R₂ denotes alkyl, alkoxy, acyl, alkoxy carbonyl or hydroxy,

R₃ denotes H or alkyl,

L₁ denotes alkylene, arylene or aralkylene,

L₂

X denotes —SO—, —SO₂—, —CO— or —O—, and

m denotes 0, 1 or 2,

wherein

L₃ and L₄ together contain 3 to 5 C atoms.

The compounds of formula I preferably have a molecular weight of at least 650. They are used in particular in an amount of 5 to 1500 mg/m², preferably 10 to 500 mg/m² of colour photographic material.

Examples of compounds according to the invention are:

a) L₃=L₄=—CH₂—CH₂—; linkage of the —O—L₁—L₂—R₁ group para to the nitrogen; position of R₂ given with respect to O.

$X = SO_2$; $m = 0$;$X = SO_2$; $m = 1$; $R_2 = o\text{-Cl}$;$X = SO_2$; $m = 0$;$X = O$; $m = 1$; $R_2 = o\text{-OCH}_3$;$X = SO_2$; $m = 1$; $R_2 = o\text{-CH}_3$;a 1:1-mixture of

I-30

I-31

I-32

In one preferred embodiment, the layer containing the magenta coupler also contains at least one compound of formula II or III in addition:

(II) 25

30

wherein

R₂₁ denotes alkyl, aryl, alkoxy, aryloxy, hydroxy, acyl, alkoxy carbonyl, aryloxy carbonyl, carbamoyl, —CON(R₅)R₆, —SO₂R₅, —SO₂N(R₅)R₆, aryloxy carbonyl, alkyl or alkenyl,

R₂₂ denotes R₂₁ or halogen, and

r denotes 0 or an integer from 1 to 4,

wherein a plurality of radicals R₂₂ may be the same or different.

The compounds of formulae (II and (III) are used in a total amount of 5 to 1500 mg/m² in each case, preferably 10 to 750 mg/m².

Examples of compounds of formulae II and III are:

R₁₁ denotes H, acyl, alkoxy carbonyl, —CON(R₅)R₆, —SO₂R₅, —SO₂N(R₅)R₆, aryloxy carbonyl, alkyl or alkenyl,

R₁₂ denotes alkyl, aryl, aralkyl, alkenyl, halogen, alkoxy, acyloxy, aryloxy, acyl, acyl-amino, —CON(R₅)R₆, alkoxy carbonyl amino, —N(R₆)CON(R₅)R₆, alkoxy carbonyl or aryloxy carbonyl,

p, q denote 0 or a number from 1 to 4,

L₁₁ denotes

50

55

II-1

R₁₃ denotes H, alkyl, aryl, acyl, alkoxy carbonyl, —CON(R₅)R₆ or aryloxy carbonyl,

wherein a plurality of radicals R₁₂, R₁₃ may be the same or different, and one substituent is situated para to the OH or OR₁₁ in each case,

III-6

III-7

Examples of colour photographic materials include colour negative films, colour reversal films, colour positive films, colour photographic paper, colour reversal photographic paper, and colour-sensitive materials for the colour diffusion transfer process or the silver halide bleaching process.

III-1

Photographic materials consist of a support on which at least one light-sensitive silver halide emulsion layer is deposited. Thin films and foils are particularly suitable as supports. A review of support materials and of the auxiliary layers which are deposited on the front and back thereof is given in Research Disclosure 37254, Part 1 (1995), page 285 and in Research Disclosure 38957, Part XV (1996), page 627.

III-2

Colour photographic materials usually contain at least one red-sensitive, at least one green-sensitive and at least one blue-sensitive silver halide emulsion layer, and optionally contain intermediate layers and protective layers also.

III-3

Depending on the type of photographic material, these layers may be arranged differently. This will be illustrated for the most important products:

Colour photographic films such as colour negative films and colour reversal films comprise, in the following sequence on their support: 2 or 3 red-sensitive, cyan-coupling silver halide emulsion layers, 2 or 3 green-sensitive, magenta coupling silver halide emulsion layers, and 2 or 3 blue-sensitive, yellow-coupling silver halide emulsion layers. The layers of identical spectral sensitivity differ as regards their photographic speed, wherein the less sensitive partial layers are generally disposed nearer the support than are the more highly sensitive partial layers.

A yellow filter layer is usually provided between the green-sensitive and blue-sensitive layers, to prevent blue light from reaching the layers underneath.

The options for different layer arrangements and their effects on photographic properties are described in J. Inf Rec Mats., 1994, Vol. 22, pages 183–193, and in Research Disclosure 38957, Part XI (1996), page 624.

Colour photographic paper, which as a rule is less sensitive to light than is colour photographic film, usually comprises the following layers on the support, in the following sequence: a blue-sensitive, yellow-coupling silver halide emulsion layer, a green-sensitive, magenta coupling silver halide emulsion layer, and a red-sensitive, cyan-coupling silver halide emulsion layer.

Departures from the number and arrangement of the light-sensitive layers may be effected in order to achieve defined results. For example, all the high-sensitivity layers may be combined to form a layer stack and all the low-sensitivity layers may be combined to form another layer stack in a photographic film, in order to increase the sensitivity (DE 25 30 645).

The essential constituents of the photographic emulsion layer are the binder, the silver halide grains and colour couplers.

Information on suitable binders is given in Research Disclosure 37254, Part 2 (1995), page 286, and in Research Disclosure 38957, Part IIa (1996), page 598.

Information on suitable silver halide emulsions, their production, ripening, stabilisation and spectral sensitisation, including suitable spectral sensitisers, is given in Research Disclosure 37254, Part 3 (1995), page 286, in Research Disclosure 37038, Part XV (1995), page 89, and in Research Disclosure 38957, Part VA (1996), page 603.

Photographic materials which exhibit camera-sensitivity usually contain silver bromide-iodide emulsions, which may also optionally contain small proportions of silver chloride. Photographic copier materials contain either silver chloride-bromide emulsions comprising up to 80 mole % AgBr, or silver chloride-bromide emulsions comprising more than 95 mole % AgCl.

Information on colour couplers is to be found in Research Disclosure 37254, Part 4 (1995), page 288, in Research Disclosure 37038, Part II (1995), page 80, and in Research Disclosure 38957, Part XB (1996), page 616. The maximum absorption of the dyes formed from the couplers and from the colour developer oxidation product preferably falls within the following ranges: yellow couplers 430 to 460 nm, magenta couplers 540 to 560 nm, cyan couplers 630 to 700 nm.

In order to improve sensitivity, granularity, sharpness and colour separation, compounds are frequently used in colour photographic films which on reaction with the developer oxidation product release compounds which are photographically active, e.g. DIR couplers, which release a development inhibitor.

Information on compounds such as these, particularly couplers, is to be found in Research Disclosure 37254, Part

5 (1995), page 290, in Research Disclosure 37038, Part XIV (1995), page 86, and in Research Disclosure 38957, Part XC (1996), page 618.

The colour couplers, which are mostly hydrophobic, and other hydrophobic constituents of the layers also, are usually dissolved or dispersed in high-boiling organic solvents. These solutions or dispersions are then emulsified in an aqueous binder solution (usually a gelatine solution), and after the layers have been dried are present as fine droplets (0.05 to 0.8 mm diameter) in the layers.

Suitable high-boiling organic solvents, methods of introduction into the layers of a photographic material, and other methods of introducing chemical compounds into photographic layers, are described in Research Disclosure 37254, Part 6 (1995), page 292.

The light-insensitive intermediate layers which are generally disposed between layers of different spectral sensitivity may contain media which prevent the unwanted diffusion of developer oxidation products from one light-sensitive layer into another light-sensitive layer which has a different spectral sensitivity.

Suitable compounds (white couplers, scavengers or DOP scavengers) are described in Research Disclosure 37254, Part 7 (1995), page 292, in Research Disclosure 37038, Part III (1995), page 84, and in Research Disclosure 38957, Part XD (1996), page 621.

The photographic material may additionally contain compounds which absorb UV light, brighteners, spacers, filter dyes, formalin scavengers, light stabilisers, anti-oxidants, D_{Min} dyes, additives for improving the dye-, coupler- and white stability and to reduce colour fogging, plasticisers (latices), biocides and other substances.

Suitable compounds are given in Research Disclosure 37254, Part 8 (1995), page 292, in Research Disclosure 37038, Parts IV, V, VI, VII, XI and XIII (1995), pages 84 et seq., and in Research Disclosure 38957, Parts VI, VIII, IX, X (1996), pages 607, 610 et seq.

The layers of colour photographic materials are usually hardened, i.e. the binder used, preferably gelatine, is crosslinked by suitable chemical methods.

Suitable hardener substances are described in Research Disclosure 37254, Part 9 (1995), page 294, in Research Disclosure 37038, Part XII (1995), page 86, and in Research Disclosure 38957, Part IIB (1996), page 599.

After image-by-image exposure, colour photographic materials are processed by different methods corresponding to their character. Details on the procedures used and the chemicals required therefor are published in Research Disclosure 37254, Part 10 (1995), page 294, in Research Disclosure 37038, Parts XVI to XXIII (1995), page 95 et seq., and in Research Disclosure 38957, Parts XVIII, XIX, XX (1996), together with examples of materials.

The magenta couplers are preferably those which have pyrazolotriazole structures of formulae (IV) or (V):

In one particularly preferred embodiment, at least one light-insensitive layer contains a compound of formula VI or VII

(VI) 5

wherein

R_{41} denotes alkyl, alkoxy, alkylamino, aryl, aryloxy or arylamino, and

R_{41} contains at least 12 C atoms.

(VI) 10

wherein

R_{51} , R_{52} denote alkyl, alkoxy, acylamino, acyloxy, alkoxy carbonylamino, $N\epsilon$ -alkylureido, $N\epsilon$ -arylureido or sulphonylamino, and

R_{53} denotes H, alkyl, acyl, alkyl carbamoyl, alkoxy carbamoyl, alkyl sulfonyl,

r, s denote 0, 1 or 2, and

wherein a plurality of radicals R_{51} , R_{52} may be the same or different and adjacent radicals R_{51} and R_{52} can form a 5- to 6-membered ring.

R_{41} is preferably alkyl,

R_{51} is preferably alkyl or alkoxy,

R_{52} is preferably alkyl, and

r, s are preferably 0 or 1.

The compounds of formulae (VI) and (VII) are used in a total amount of 5 to 1000 mg/r² in each case, preferably 10 to 500 mg/m².

Examples of compounds of formulae (VI) and (VI) are:

VI-1 $R_{41}=C_{11}H_{23}$

VI-2 $R_{41}=C_{15}H_{31}$

VI-3 $R_{41}=C_6H_{13}/-CH-CH_2H_{17}$

VI-4 $R_{41}=C_{17}H_{35}$

VII-1 $R_{51}=C_8H_{17-t}$, $R_{52}=H$, $R_{53}=H$

VII-2 $R_{51}=CH_3$, $R_{52}=C_4H_{9-t}$, $R_{53}=H$

VII-3 $R_{51}=C_8H_{17-t}$, $R_{52}=CH_3$, $R_{53}=H$

VII-4 $R_{51}=R_{52}=C_4H_{9-t}$, $R_{53}=H$

VII-5 $R_{51}=R_{52}=C_5H_{11-t}$, $R_{53}=H$

VII-6 $R_{51}=C_4H_{9-t}$, $R_{52}=OCH_3$, $R_{53}=H$

VII-7 $R_{51}=t-C_8C_{17}$, $R_{52}=H$, $R_{53}=COCH=CH_2$

VII-8 $R_{51}=CH_3$, $R_{52}=t-C_4H_9$, $R_{53}=COCH=CH_2$

VII-9 $R_{51}=R_{52}=t-C_5H_{11}$, $R_{53}=COOC_2H_5$

VII-10 $R_{51}=R_{52}=t-C_4H_9$, $R_{53}=CONHC_4H_9$

The radicals R_{52} are situated in the ortho position in relation to oxygen.

Emulsions containing more than 80 mole % AgCl, particularly more than 95 mole % AgCl, are preferably used as the light-sensitive silver halide emulsion; AgBrCl emulsions containing 95 to 99.5 mole % AgCl are most preferably used.

Synthesis of I-2

A mixture of 41.2 g S,S-dioxo-N-(4-(2-hydroxydodecyloxy)-phenyl)-thiazane, 9.9 g isophorone diisocyanate and 250 ml xylene was heated at 120° C. for 30 hours. Thereafter, the xylene was completely removed by distillation under vacuum. 50.5 g I-2 were obtained as a brownish yellow resin.

Synthesis of I-8

A solution of 16 g phosphoric acid isotridecyl ester dichloride in 50 ml CH_2Cl_2 was added drop-wise at 0° C. to a solution of 29.8 g N-(4-(4-amminobutoxy)phenyl)-S,S-dioxothiazane in 100 ml CH_2Cl_2 and 50 ml pyridine, and the batch was allowed to warm up to 20° C. It was stirred for 6 hours, and the organic phase was washed with water, 10 % by weight hydrochloric acid and half-saturated common salt solution. After the complete removal of the solvent, 33 g I-8 were obtained as a slightly yellow solid which had solidified in a glassy form.

Synthesis of I-31

12.6 g methanesulphonic acid chloride were added drop-wise at 0° C. to a solution of 33.3 g polytetrahydrofuran (M=660) and 11.2 g triethylamine in 500 ml CH_2Cl_2 and the batch was allowed to warm up to 20° C. with stirring. After 2 hours, the precipitate was filtered off and the organic phase was washed with water. 5 % by weight hydrochloric acid, 5 % by weight aqueous sodium hydroxide solution and saturated common salt solution. The solvent was removed completely. The viscous oil was dissolved in 250 ml DMF, 24.6 g S,S-dioxo-N-(4-hydroxyphenyl)-thiazane and 15 g K_2CO_3 were added thereto and the batch was heated to 95° C. for 48 hours. The reaction mixture was added to 750 ml water and was extracted three times with 200 ml ethyl acetate each time. The organic phase was washed with half-saturated common salt solution, 10% by weight aqueous sodium hydroxide solution and water. After complete concentration by evaporation, 52.6 g I-31 were obtained as a dark yellow, viscous oil.

EXAMPLES

Example 1

A colour photographic recording material was produced by depositing the following layers in the given sequence on

a film base comprising paper coated on both sides with polyethylene. The quantitative data are given with respect to 1 m² in each case. The corresponding amounts of AgNO₃ are quoted for silver halide deposition.

Layer structure 1	5
Layer 1 (substrate layer)

The following were used as comparison compounds:

TABLE 2-continued

V-1	Layer structure	DD _{0.6}	DD _{1.0}
		13(I)	-37
5	14(I)	-29	-20

V-2	As Table 2 shows, the dye stabilisers according to the invention are more effective than the comparison compounds V-1, V-2 and V-3. The stability in relation to light is improved again by the use of compounds of formulae VI or VII as DOP scavengers, instead of EF-1 and/or EF-2.
10	What is claimed is:

15 1. A color photographic material which comprises a support and containing at least one light-sensitive silver halide emulsion layer and at least one color coupler associated with this layer, and the silver halide emulsion layer contains at least one compound of formula (I)

TABLE 1

Layer structure	Layer 2		Layer 3		Layer 4		Layer 5		Layer 6	
	Yellow coupler	Stabiliser	DOP scavenger	Magenta coupler	Stabiliser	Oil former	DOP scavenger	Cyan coupler		
1 (C)	Y-1/Y-2	ST-1	EF-1/EF-2	M-17	V-1 (210)/ST3	DIDP/ITD	EF-1/EF-2	C-1

14 (I)	"		VI-4 (50)	"	I-21 (30)/II-5	"	VII-4 (50)	"		

The samples were subsequently exposed to the light of a 50 klux xenon lamp, normalised to daylight, in a light/dark sequence at 30×10^6 lux (light phase: 3.5 hours, 45° C., 50 % relative humidity / dark phase: 1.5 hours, 30° C., 85% relative humidity). The percentage changes in magenta densities were determined for initial densities D=0.6 and D=1.0 (DD_{0.6}, DD_{1.0}) (Table 2).

(I)

wherein

m is 0, 1, 2, 3 or 4,

n is 2, 3, 4, 5 or 6,

R₁ is a di- to hexavalent group,R₂ is alkyl, alkenyl, cycloalkyl, aryl, alkoxy, aryloxy, alkylthio, arylthio, acyl,alkoxycarbonyl, aryloxycarbonyl, hydroxy, halogen, cyano, $-\text{SO}_2\text{R}_5$, $-\text{SOR}_5$, $-\text{CON}(\text{R}_5)\text{R}_6$ or $-\text{SO}_2\text{N}(\text{R}_5)\text{R}_6$,L₁ is alkylene, arylene, aralkylene or alkylidene,

TABLE 2

Layer structure	DD _{0.6}	DD _{1.0}
1(C)	-71	-55
2(C)	-82	-60
3 (I)	-52	-40
4 (I)	-49	-38
5 (I)	-39	-31
6 (I)	-40	-32
7(C)	-77	-57
8 (I)	-57	-42
9 (I)	-55	-41
10 (I)	-42	-33
11(C)	-48	-37
12 (I)	-38	-28

L_2 isL_3 and L_4 are identical or different and are a C_1 – C_3 alkylene which is optionally substituted,

 X isR_3 is H, acyl, $-\text{SO}_2\text{R}_5$, alkoxy carbonyl, aryloxy carbonyl, alkyl, aryl, alkenyl or the radical of a heterocycle,

R_4 is H, alkyl, aryl or the radical of a heterocycle,

R_5 is alkyl or aryl, and

R_6 is H, alkyl or aryl, wherein

2 radicals R_3 and R_4 may be the same or different and at least one light-sensitive layer contains a compound of formula VI or VII

wherein

R_{41} is alkyl, alkoxy, alkyamino, aryl, aryloxy or arylamino, and R_{41} contains at least 12 C atoms.

wherein

R_{51} and R_{52} are identical or different and are alkyl, alkoxy, acylamino, acyloxy, alkoxycarbonyl, N^1 -alkyl-ureido, N^1 -arylureido or sulphonylamino, and R_{53} is H, alkyl, acyl, alkyl carbamoyl, alkoxy carbonyl or alkyl sulfonyl,

r and s are identical or different and are 0, 1 or 2, and wherein a plurality of radicals R_{51} and R_{52} may be the same or different and adjacent radicals R_{51} and R_{52} can form a 5- to 6-membered ring.

2. The color photographic material according to claim 1, wherein

R_1 is a di- to hexavalent aliphatic or aromatic group, R_2 is alkyl, alkoxy, acyl, alkoxycarbonyl or hydroxy,

R_3 is H or alkyl,

L_1 is alkylene, arylene or aralkylene,

L_2 is

X is $-\text{SO---, ---SO}_2\text{---, ---CO--- or ---O---, and}$
 m is 0, 1 or 2, wherein

L_3 and L_4 together contain 3 to 5 C atoms.

3. The color photographic material according to claim 1, wherein the compounds of formula I have a molecular weight of at least 650.

4. The color photographic material according to claim 1, wherein the compounds of formula I are used in an amount of 5 to 1500 mg/m² of the photographic material.

5. The color photographic material according to claim 1, wherein color coupler is magenta coupler.

6. The color photographic material according to claim 5, wherein the magenta coupler is a pyrazolotriazole magenta coupler.

7. The color photographic material according to claim 1, wherein the coupler-containing silver halide emulsion layer additionally contains at least one compound of formulae II or III:

wherein

R₁₁ is H, acyl, alkoxy carbonyl, —CON(R₅)R₆, —SO₂R₅, —SO₂N(R₅)R₆, aryloxy carbonyl, alkyl or alkenyl,

R₁₂ is alkyl, aryl, aralkyl, alkenyl, halogen, alkoxy, acyloxy, aryloxy, acyl, acylamino, —CON(R₆)R₆, alkoxy carbonyl amino, —N(R₆)CON(R₅)R₆, alkoxy carbonyl or aryloxy carbonyl,

p and q are identical or different and are 0 or a number from 1 to 4,

L₁₁ is —S—, —SO—, —SO₂—, —C=O— or

R₁₃ is H, alkyl, aryl, acyl, alkoxy carbonyl, —CON(R₅)R₆ or aryloxy carbonyl,

wherein a plurality of radicals R₁₂ and R₁₃ may be the same or different, and one substituent is situated para to the OH or OR₁₁ in each case;

wherein

R₂₁ is alkyl, aryl, alkoxy, aryloxy, hydroxy, acyl, alkoxy carbonyl, aryloxy carbonyl, —CON(R₅)R₆, —SO₂R₅, —SO₂N(R₅)R₆, alkoxy carbonyl amino, —N(R₆)CON(R₅)R₆ or acyloxy.

R₂₂ is R₂₁ or halogen, and

r is 0 or an integer from 1 to 4,

wherein a plurality of radicals R may be the same or different.

(II)

8. The color photographic material according to claim 7, wherein the compounds of formulae II and III are used in a total amount of 50 to 1500 mg/m² of the color photographic material.

5 9. The color photographic material according to claim 6, wherein said pyrazolotriazole magenta coupler is of the formulae (IV) or (V)

(IV)

(V)

wherein

X₃₁ is H or a group which is split off under the conditions of chromogenic development,

R₃₁ is an alkyl, which is optionally substituted, and

R₃₂ is R₃₁, or aryl,

wherein the sum of all the C atoms of Radicals R₃₁ and R₃₂ in a coupler molecule is at least 12.

30 10. The color photographic material according to claim 9, wherein the compounds of formulae VI and VII are used in a total amount of 5 to 1000 mg/m².

35 11. The color photographic material according to claim 1, wherein the compounds of formulae VI and VII are used in a total amount of 10 to 500 mg/m².

40 12. The color photographic material according to claim 7, wherein the compounds of formulae II and III are used in a total amount of 5 to 1500 mg/m² of the color photographic material.

45 13. The color photographic material according to claim 7, wherein the compounds of formulae II and III are used in a total amount of 10 to 750 mg/m² of the color photographic material.

14. The color photographic material according to claim 11, wherein the compounds of formula I are used in an amount of 10 to 500 mg/m² of the photographic material.
